UNITED STATES PATENT OFFICE.

MAX MARQUARDT AND EMIL HÖFFNER, OF DRESDEN, GERMANY.

STEAM-SUPERHEATER.

SPECIFICATION forming part of Letters Patent No. 727,400, dated May 5, 1903.

Application filed April 12, 1902. Serial No. 102,623. (No model.)

To all whom it may concern:

Be it known that we, MAX MARQUARDT, residing at 31 Christianstrasse, and EMIL HÖFFNER, residing at 3 Ludwig-Richterstrasse, Dresden, in the Kingdom of Saxony and Empire of Germany, subjects of the King of Saxony, have invented new and useful Improvements Relating to Steam-Superheaters, of which the following is a specification.

Our invention relates to steam-superheaters, and comprises an arrangement in connection with the generator whereby the radiating heat of the fire will be utilized and the action of too high temperatures upon the superheater-tubes will be precluded without reducing their effectiveness.

The invention consists substantially in providing the generator in front with a chamber in the upper part of which the superheater is built, so that the heat radiated by the fire will reach the same.

In the accompanying drawings we have shown the boiler of a portable engine comprising this improved arrangement.

Figure 1 is a longitudinal section through the fire-box and the front chamber. Fig. 2 is partly a transverse section through the chamber and partly a front elevation.

To the front wall *a* of the boiler is attached a chamber *c*, partly lined with refractory material *b*. This chamber, which is closed in front by a door *d* and terminates at the rear in the fire-box or furnace, is covered up by the bottom plate *f* of the superheater-chamber, wherein the superheater-tubes *g* are secured, the lower part *k* of which may be rearwardly inclined, as shown. Above the aforesaid bottom plate *f* of the superheater are arranged in the well-known manner the two steam-chambers *h* *i*, to one of which the fresh steam is admitted, while the other delivers the superheated steam.

In the front chamber *c* may be provided a slide or flap *m*, which is raised, more particularly when firing the boiler, to exclude the tubes from the action of too great a heat. By this slide or flap the stoker is enabled without the exercise of special attention to admit heat to the superheater-tubes or to shut it off from them, according to exigencies.

What we claim as our invention, and desire to secure by Letters Patent, is—

1. The combination with a steam-boiler furnace having a chamber in front of its fire-box, and through which the fuel is introduced, of a superheater within said chamber out of the path of the furnace-gases and exposed to the radiated heat from the fire, substantially as described.

2. The combination with a steam-boiler furnace having in front of the fire-box a chamber through which the fuel is introduced, of a generator depending into said chamber out of the path of the furnace-gases, with the lower end exposed to the radiated heat from the fire-box, substantially as described.

3. The combination with a steam-boiler furnace having a chamber in front of its fire-box, of a superheater located in said chamber between the furnace-door and grate-bars to one side of the path of the entering fuel and out of the path of the furnace-gases, and exposed at its inner end to the radiated heat from the fire-box.

4. The combination with a steam-boiler furnace having a chamber exterior to its fire-box, of a superheater in said chamber and having its inner end without the fire-box and out of the path of the furnace-gases, but exposed to the radiated heat therefrom, substantially as described.

5. The combination with a steam-boiler furnace, and a superheater having its inner end without the fire-box and out of the path of the furnace-gases, but exposed to the radiated heat therefrom, of a movable shield or flap to cover said superheater, and exclude the same from too great heat, substantially as described.

6. The combination with a steam-boiler furnace, having a fuel-inlet chamber, between its door and fire-box and open at the top, of a superheater mounted in said top opening with its lower end exposed to the radiated heat from the fire-box, substantially as described.

7. The combination with a steam-boiler furnace, having a fuel-inlet chamber between its door and fire-box, and open at the top, of a superheater, closing the said open top and comprising inlet and outlet chambers, and a

series of looped or U-shape tubes, connected at their ends to the respective steam-chambers and exposed at their bends to the radiated heat from the fire-box, substantially as described.

5. 8. The combination with a steam-boiler furnace having a fuel-inlet chamber between the door and fire-box, and open at the top, of a superheater closing said top, and having depending U-shape tubes inclined at their bends

at K to receive the radiated heat from the fire-box.

In testimony whereof we have signed our names to this specification in the presence of two subscribing witnesses.

MAX MARQUARDT.
EMIL HÖFFNER.
